METHOD OF AND MEANS FOR INSTALLING
SUBDRAIN PIPEFirman L. Carswell, Johnson County, Kans., and
Otto W. Schmidt, Kansas City, Mo.

Application June 21, 1939, Serial No. 280,330

10 Claims. (Cl. 61—63)

This invention relates to the method of and means for installing subdrain pipes, and particularly for installing drain pipe beneath roadways, railroads, etc., where it is important that the drain pipe be encased in a pervious material.

In the maintenance of paved roadways, railroad beds, etc., it is very important to keep the sub-grades free from the accumulation of excessive water which might materially lead to the rapid destruction of the superstructure. Fast moving, heavy traffic passing over the roadway or railroad soon causes a breaking down of the superstructure above the water pocket, thereby necessitating expensive repairs.

Drainage tubes have been used to drain excessive water beneath the roadways, etc., but in view of the fact that it is deemed advisable to encase the drainage tube in a pervious material, such as crushed rock, to maintain the openings to the tube in proper condition and to support the road loads, it has been found necessary to cut away and replace the surfacing material during the placement of the drainage tubes. Due to the fact that this operation is very expensive and interferes with the use of the roadway during the repair work, it has not been deemed advisable in many instances.

The principal object of the present invention is the provision of a method whereby drain pipe can be easily and quickly encased in a pervious material beneath a road surfacing material without disturbing the surfacing material of the road and without interfering with the traffic thereover.

A further object of this invention is the provision of a device for encasing a drain pipe in a pervious material, including said drain pipe as a part of said means.

Other objects will appear during the course of the specification, wherein reference is had to the drawings in which:

Figure 1 is a perspective view of a tamping tool used in carrying out the method of this invention.

Fig. 2 is a perspective view of the trough and drainage tube in operative relation.

Fig. 3 is an enlarged sectional view of the equipment in position, taken on line III—III of Fig. 10.

Fig. 4 is an enlarged cross sectional view taken on line IV—IV of Fig. 2.

Fig. 5 is a longitudinal sectional view of a series of troughs partially positioned on the drain pipe.

Fig. 6 is a side elevation of the tamping tool. Fig. 7 is a plan view of the tamping tool.

Fig. 8 is a plan view of a paved roadway, showing the positioning of drainage tubes thereunder.

Fig. 9 is a sectional view of a paved roadway showing a hole bored in the sub-structure with the drain pipe positioned therein.

Fig. 10 is a sectional view similar to that shown in Fig. 9, with the troughs and tamper in position.

Fig. 11 is a sectional view of the roadway showing the drainage tube installed.

Fig. 12 is a modified form showing a specially constructed trough, having means whereby it is secured for longitudinal movement on a round drain tube; and,

Fig. 13 is a fragmentary elevational view of the parts as shown in Fig. 12.

Throughout the several views, like reference characters designate similar parts and the numeral 20 is a drain pipe of semi-circular form having flanges 22, and drainage openings 24 beneath the corrugated top 26. This drainage pipe is suitable for positioning in the sub-soil for draining surplus water therefrom, and when properly embedded in crushed rock, it will support heavy loads of traffic on the paved surface.

A sectional trough 28 consists of a series of trough units 30 joined together by U-shaped members 32 which are secured to adjacent abutting trough units, by means of bolts 34 passing through holes 36. Any desirable length of trough 28 may be had by joining together the proper number of units 30.

Each trough unit is provided with an inwardly turned angle iron 38 which extends below the bottom of the trough a sufficient distance to form a groove 40 suitable to receive the flanges 22 of the drainage pipe, thus making it possible to secure the trough to the drainage tube for longitudinal movement therealong.

A tamping tool 42 comprises a head 44 having a sectional handle 46, by means of which the head is moved lengthwise of said trough to position a pervious material, such as chat, as a fill about the drainage pipe, as hereinafter set forth.

The tamper head 44 is substantially the frustum of a pyramid with a forwardly projecting lower lip 48 which is adapted to rest on the bottom of the trough 28, during the tamping operation. The enlarged end of the head is provided with a top extension 50 which functions to move the pervious material to position about the drainage pipe.

The tamper handle 46 comprises a series of sections 47, threaded at 49 and joined together by couplings 51. For convenience of operation, sections 47 may be removed as the tamping operation proceeds and the length of the hole is reduced.

Referring to Figs. 12 and 13, it will be noted that trough 28 is shown mounted on a round drainage pipe 52. It will also be noted that the trough is provided with downwardly converging members that serve to engage the walls of the drain pipe below the center line thereof, thus precluding transverse separation of the joined parts. The upper edges of trough 28 are shown rolled as at 54.

Referring now to the method of installing sub-drain pipe, reference will be had to Figs. 8, 9, 10 and 11.

Fig. 1 is a plan view of a highway having a sectional slab surface 60 with the usual transverse expansion joints 62 and shoulders 64. The dotted lines indicate a typical installation of the subdrainage pipe.

The first step in the procedure is to form a trench across the shoulder 64 at right angles to the roadway or whatever angle is desired for positioning the drainage tube. The second step is the forming of a hole beneath the paving at an outwardly and downwardly inclined angle, sufficient to properly drain the pipe. This hole is made of much greater cross sectional area than that of the drainage pipe, to be used so as to permit of a sufficient amount of refill material to surround the drainage pipe. Any earth between the top of the bored hole and the bottom surface of the paving is broken down and raked from the hole. In some instances the circular, bored hole will be used without the removal of any dirt from the top thereof.

The hole is usually bored to extend to or beyond the center line of the roadway, but may be of any length or position to meet the particular drainage problem.

The drainage pipe is now positioned in the hole and care is taken to see that it has an even bearing throughout its length. The trough 28 is now slid to position over the drainage tube, with its end positioned a short distance from the inner end of the drainage pipe. A small quantity of pervious material, such as crushed rock, is now shoveled into the protruding end portion of the trough 28, and is rammed to the back of the hole or tunnel by means of the tampering tool 42.

When the inner end of the hole is tamped full, the trough is slipped outwardly to permit the positioning of more crushed rock without embedding the end of the trough therein. This operation is repeated until the tunnel is completely filled and the drainage pipe beneath the paving is completely encased in the pervious material.

The last step, is the laying of the line of pipe 70 across the shoulder to the road-side ditch 72, and the refilling of ditch 66.

During the progress of the tunnel refilling operation, sections of the trough 28 and tool handle 42 may be removed.

It is apparent that this method of positioning a drainage pipe, properly encased in a shield of pervious material within a tunnel formed beneath a pavement, provides an extremely rapid and economical method of installation with the removal of a minimum amount of the road bed material, and without interfering with the usual traffic over the roadway.

Having thus described the invention, what is claimed as new and desired to be secured by Letters Patent is:

1. Means for installing a subdrain pipe in a tunnel comprising a drainage pipe; a trough slidably secured to said drainage pipe positioned in said tunnel; and a tampering tool operable within said trough whereby a pervious material is tamped in said tunnel about said drainage pipe.

2. Means for installing a subdrain pipe in a tunnel comprising a drainage pipe adapted to be positioned in said tunnel; a trough secured to said drainage pipe for relative longitudinal movement therealong; and a tampering tool operable in said trough whereby pervious material deposited in the trough is positioned to encase said drainage pipe in said channel.

3. Means for installing a subdrain pipe in a casing of pervious material within a tunnel, comprising a drainage pipe adapted to be positioned within said tunnel; a sectional trough secured to said drainage tube for relative longitudinal movement thereon; and a tampering tool operable in said trough to move pervious material deposited in the trough outside said tunnel to a position within said tunnel and about said drainage pipe.

4. Means for installing a subdrain pipe in a casing of pervious material within a tunnel comprising a drainage pipe having outwardly extending top flanges and adapted to be positioned in said tunnel; a sectional trough having grooves formed in the bottom portion thereof to receive the drain pipe flanges whereby the trough is secured for longitudinal relative movement thereon; and a tampering tool adapted to be reciprocated in said trough to deliver a pervious material to the end thereof and tamp it about said drain pipe.

5. Means for installing a subdrain pipe in a casing of pervious material within a tunnel comprising a drainage pipe having outwardly extending top flanges and adapted to be positioned in said tunnel; a sectional trough having grooves formed in the bottom portion thereof to receive the drain pipe flanges whereby the trough is secured for longitudinal relative movement thereon; and a tampering tool having a forwardly projecting lower lip adapted to be reciprocated in said trough to cause a pervious material, delivered to said trough, to be moved to a position about said drainage pipe.

6. The method of encasing a drainage pipe in a coating of pervious material within a tunnel, comprising inserting said drainage pipe into said tunnel; positioning a trough for longitudinal movement on said drainage pipe with the inner end thereof spaced apart from the inner end of said drainage tube and with the outer end portion of said trough extended outside said tunnel; introducing a quantity of pervious material into said trough; reciprocating a tampering tool in said trough to move said pervious material to a tamped position about that portion of the drainage pipe beyond said trough; moving the trough to a distance outwardly along said drainage pipe and again tamping pervious material about said drainage tube; continuing this operation until the portions of the drainage tube within the tunnel is encased in said pervious material.

7. The method of encasing a drainage pipe in a coating of pervious material within a tunnel comprising inserting said drainage pipe into said tunnel; positioning a trough for longitudinal movement on said drainage pipe with the inner end thereof spaced apart from the inner end of

5 said drainage tube and with the outer end portion of said trough extended outside said tunnel; introducing a quantity of pervious material into said trough; reciprocating a tamping tool in said trough to move said pervious material to a tamped position about that portion of the drainage pipe beyond said trough; repeating this operation until that portion of the drainage tube beyond the trough is encased in the pervious material; moving the trough outwardly along said drainage pipe a short distance and again repeating the operation of tamping pervious material about that portion of the drainage tube between the trough and the pervious material previously tamped; then continuing these trough moving and tamping operations until the tunnel is completely filled.

8. The method of encasing a drainage pipe in a coating of pervious material within a tunnel comprising inserting said drainage pipe into said tunnel with a portion thereof positioned outside the tunnel; positioning a trough for longitudinal movement on said drainage pipe with the inner end thereof spaced apart from the inner end of said drainage tube and with the outer end portion of said trough extended outside said tunnel; introducing a quantity of pervious material into said trough; reciprocating a tamping tool in said trough to move said pervious material to a tamped position about that portion of the drainage pipe beyond said trough; moving the trough a distance outwardly along said drainage pipe and again tamping pervious material about said drainage tube; continuing this operation until the

portion of the drainage tube within the tunnel is encased in said pervious material.

9. The method of encasing a drainage pipe in a coating of pervious material within a tunnel comprising inserting said drainage pipe in said tunnel; mounting a trough in said tunnel with its inner end portion spaced outwardly from the inner end of said drainage pipe delivering a pervious material along said trough to encase that portion of the drainage pipe beyond said trough; moving said trough outwardly a short distance and again delivering pervious material to encase another section of the drainage pipe; and continuing the outward adjustment of the trough and the delivery of material therethrough until the drainage pipe within the tunnel is completely encased in pervious material.

10. The method of encasing a drainage pipe in a coating of pervious material within a tunnel comprising inserting said drainage pipe in said tunnel; mounting a trough in said tunnel with its inner end portion spaced outwardly from the inner end of said drainage pipe delivering a pervious material along said trough and tamping the same to encase that portion of the drainage pipe beyond said trough; moving said trough outwardly a short distance and again delivering and tamping pervious material to encase another section of the drainage pipe; and continuing the outward adjustment of the trough and the delivery of material therethrough and tamping the same until the drainage pipe within the tunnel is completely encased in pervious material.
